CLAIM

The ornamental design for a door for clothes management apparatus, as shown and described.

DESCRIPTION

FIG. 1 is a front perspective view of the door for clothes management apparatus showing our new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the door for clothes management apparatus that form no part of the claimed design.

1 Claim, 7 Drawing Sheets
